[21] Appl. No.: 686,722

[57] CLAIM

The ornamental design for a container for pills, as shown.

[22] Filed: May 17, 1976

DESCRIPTION

FIG. 1 is an elevational view of a container for pills showing our new design.

FIG. 2 is a bottom plan view.

FIG. 3 is a top plan view; and

FIG. 4 is an elevational view looking from the right of FIG. 1.
